CLAIM

We claim the ornamental design for an embossed paper product, as shown and described.

DESCRIPTION

FIG. 1 is a top plan view of an embossed paper product bearing a repeating emboss pattern embodying our new design; and,

FIG. 2 is an enlarged fragmentary perspective view thereof, shown broken away for ease of illustration.

The embossed paper product has no substantial thickness. The opposite side of the embossed paper product of FIG. 1 is a mirror image of FIG. 1. The broken line boundaries on FIG. 1 indicate that the product has indeterminate length and width and that the claimed design repeats uniformly throughout the length and width of the product. The broken lines form no part of the claimed design.
